UNITED STATES PATENT OFFICE.

JOHN ÓVÁRY, OF NEW YORK, N. Y.

ADVERTISING DEVICE.

SPECIFICATION forming part of Letters Patent No. 790,522, dated May 23, 1905.

Application filed March 20, 1905. Serial No. 250,994.

To all whom it may concern:

Be it known that I, JOHN ÓVÁRY, a citizen of the United States, residing at New York, in the county of New York and State of New York, have invented certain new and useful Improvements in Advertising Devices, of which the following is a specification, such as will enable those skilled in the art to which it appertains to make and use the same.

10 This invention relates to advertising devices; and the object thereof is to provide an improved device of this class which is designed for use in hotels, cafés, restaurants, offices, and similar places.

15 My invention comprises a book the leaves of which consist of ordinary sheets of blotter-paper, said leaves being bound together at one end and perforated transversely adjacent to said end, the book thus formed being also

20 provided with a cover the separate side portions of which are of the same shape as the leaves and the said leaves being each provided on one side with an advertisement or advertisements.

25 The invention is fully disclosed in the following specification, of which the accompanying drawings form a part, in which the separate parts of my improvement are designated by suitable reference characters in each of the

30 views, and in which—
Figure 1 is a view of my improved advertising book or device with one side of the cover turned back; Fig. 2, a view at right angles to Fig. 1, and Fig. 3 a view similar to Fig. 1 and showing one of the leaves also turned back so as to show the next adjacent leaf.

35 In the practice of my invention I provide a book comprising a plurality of leaves α , composed of ordinary blotting-paper or blotting material, and these leaves are bound together at the end α^2 thereof, and each is provided adjacent to said end with a transverse row of perforations α^3 , whereby each leaf or any one

40 45 leaf may be conveniently torn out when de-

sired. The book thus formed is also provided with a cover b , preferably composed of flexible material and bound or secured to the ends α^2 of the separate leaves α in the usual manner. 50

Each of the leaves is provided on one face or side with an advertisement or advertisements, as indicated at c in Fig. 1 and at c and d in Fig. 3, and in this way a large number of advertisements may be placed in a book of 55 this kind.

In practice my improved advertising books or devices are distributed in hotels, cafés, restaurants, and business houses of various kinds and classes and also in private houses and 60 other places, and in this way the various business concerns of any particular locality, city, or town may be provided with a cheap and effective means of advertising their particular wares. 65

Having fully described my invention, what I claim as new, and desire to secure by Letters Patent, is—

1. An advertising device, comprising a book the leaves of which are composed of blotting paper or material, said leaves being bound together at one end and being also each provided adjacent to said end with a transverse row of perforations, substantially as shown and described. 70

2. An advertising device, comprising a book the leaves of which are composed of blotting paper or material, said leaves being bound together at one end and being also each provided adjacent to said end with a transverse 80 row of perforations, said book being also provided with a cover, substantially as shown and described. 75

In testimony that I claim the foregoing as my invention I have signed my name, in presence of the subscribing witnesses, this 18th day of March, 1905. 85

JOHN ÓVÁRY.
